UNITED STATES PATENT OFFICE

PAUL E. HAVEL, OF CHICAGO, ILLINOIS, ASSIGNOR TO GEORGE I. GOLDWYN AND HERMAN GOLDWYN, BOTH OF CHICAGO, ILLINOIS, CO-PARTNERS DOING BUSINESS AS GOLDWYN BROTHERS

FOLDER FOR SEWING MACHINES

Application filed June 15, 1931. Serial No. 544,370.

This invention relates to improvement in folders for sewing machines and it consists of the matters hereinafter described and more particularly pointed out in the appended claims.

The primary object of the invention is to provide a folder of this kind especially adapted for folding over marginal parts of relatively heavy material such as burlap bagging and the like whereby said margins may be stitched to provide a strong and neat appearing seam, free from frayings and ravelings.

Another object of the invention is to provide a folder of this kind which includes parts coacting to provide a rearwardly tapering conical channel, one of which parts is so mounted with respect to the other as to yield perpendicularly to permit the free passage of the more bulky portions of the material fed therethrough for folding prior to overcasting the same in producing a finished seam.

These objects of the invention as well as others, together with the advantages thereof will more fully appear as I proceed with my specification.

In the drawings:

Fig. 1 is a view in side elevation of a folder embodying my invention, showing the same in position with respect to associated parts of a sewing machine.

Fig. 2 is a horizontal sectional view through the same as taken on the line 2—2 of Fig. 1.

Fig. 3 is a view in front elevation of the folder.

Fig. 4 is a longitudinal vertical sectional view through the same as taken on the line 4—4 of Fig. 2.

Fig. 5 is a transverse vertical sectional view through the folder as taken on the line 5—5 of Fig. 3.

Fig. 6 is a transverse vertical sectional view through the marginal seam of a burlap bag after the same has been turned inside out and before the same has been operated upon by a sewing machine equipped with my improved folder.

Fig. 7 is a view similar to Fig. 6 but

after said seam has been operated upon by a sewing machine equipped with my improved folder.

In general, my improved folder comprises a member positioned on the base of the sewing machine in advance of the usual needle and presser foot and a portion of said member is formed to provide an elevation or platform with a downwardly and rearwardly inclined top surface. Spaced laterally from one end of this elevation or platform, is an angularly disposed flange that terminates at the front edge of said member. This flange is transversely curved as it approaches the said elevation or platform and coacts with the associated end thereof to provide a rearwardly tapering, conical groove, open at the top.

Secured on said member adjacent the flange is an upstanding bracket, a part of which overhangs but is spaced above the associated groove above mentioned. This bracket is provided above said groove with a downwardly opening recess in which a block like member has a vertically guided sliding bearing and a part of this block member is provided at the bottom with a groove part forming a continuation of the first mentioned groove to complete the rearwardly tapering, conical channel of the folder. Said block member carries a guide rod that slides in said overhanging bracket and a spring surrounds said rod to normally urge said block like member downwardly, the block member and bracket having meeting parts that provide a stop to limit such downward movement.

Referring now in detail to that embodiment of the invention illustrated in the accompanying drawings: 1 indicates as a whole the base of an industrial sewing machine, and 2 indicates an end part of the overhanging arm of said machine in which is mounted a perpendicular bar 3 carrying the usual presser foot 4. Pivoted on said end part of the overhanging arm is the usual lever 5 by means of which the presser foot bar may be raised and lowered out of and into operative position with respect to the usual feed plate (not shown) projecting up

through the base. In the said end of said overhanging arm, there is mounted for reciprocation, the usual needle bar 6 carrying a needle 7 at its bottom end and associated with said needle and extending up through said base in advance of and to one side of the perpendicular plane of the needle is a loop caster 8.

The parts above described are all well known in industrial sewing machines such as are used in burlap bag renovating and like establishments, operating upon relatively heavy material.

9 indicates as a whole my improved folder which as shown herein includes a somewhat rectangular plate member resting on the base 1 of the sewing machine and having a depending flange 10 at the front by which said plate member is secured in place to the sewing machine base by screws 11. About midway between its ends there is provided on said plate member, an upright flange 12 that divides the plate member into what may be termed for convenience in future reference, as left and right hand parts or halves 13 and 14 respectively, the right hand part or half being of a lesser depth from front to rear than the left hand part. It is here pointed out that the flange 12 is inclined rearwardly toward the left and its front end takes on a curve to the right as best shown in Fig. 2.

Toward the rear end of the left hand part 13 of the plate member is provided an elevation or platform 15 having a downwardly and rearwardly inclined top surface 16 as best shown in Fig. 1. This elevation terminates at one end in spaced relation with respect to the flange 12 and said end of said platform or elevation is curved as at 17 to merge into the associated curved side of the flange 12 and coat therewith in providing a rearwardly tapering groove 18 open at the top as shown in Fig. 3. The axis of this groove is disposed a short distance to the right hand side of the perpendicular axial plane of the needle bar 6.

Detachably secured to and rising from the rear margin of the right hand part 14 of the plate member 9, adjacent the flange 12, is an upright bracket 19 having a boss 20 at its top end. In the bottom end of said boss is provided a downwardly facing opening 21 extending from front to rear. Arranged in said opening for a sliding guided bearing therein is a block like member 22 and in one side of said opening is provided an upright rib or flange 23 for engagement in a groove 24 in one side of said block member as best shown in dotted lines in Fig. 4.

In the top end of said boss is threaded a tubular bushing 25 through which slides the top end part of a guide rod or stem 26 and the bottom end thereof is screw threaded into the top end of the block member 22.

An expansion spring 27 surrounds the stem between said bushing and the top of the block like member to normally urge said member downwardly and a recess is provided in the top end of said member to accommodate the bottom end of the spring. To resist the rearward thrust on the block like member, as the material is fed rearwardly through the folder as will later appear, it is provided at the front, upon opposite sides with flanges 28 that engage coacting parts of the bracket 19 as best appears in Fig. 3.

In the bottom part of said block like member is formed a downwardly and rearwardly extending and tapering groove 29 that coacts with the groove part 18 before mentioned in providing a rearwardly tapering channel indicated as a whole by the numeral 30 in Fig. 4. At its bottom end and on that side of said block member that overhangs the associated end of the elevation or platform 15 is provided a laterally extending flange like lip 31 that is turned upwardly at its front end.

As best shown in Fig. 2, when the folder is in place upon the base of an industrial sewing machine, the axial plane of the channel 30 is disposed slightly to one side, (the right hand side) of the perpendicular axial plane of the needle bar 6.

The folder described is of especial advantage in establishments operating upon heavy material, such as for instance, in renovated used burlap bag establishments. In such establishments, the used bags are first cleaned and this is done under a high vacuum and at the same time the bags are turned inside out. This exposes an indeed frayed and raveled margin outside the original line of stitching along one side and end of the bag. This line of stitching follows about one side and the bottom of the bag in the manner well known and inwardly of said line of stitching, the edge portions of said margins are more or less frayed and raveled due to the character and relatively loose weave of the bagging.

Again, said original line of stitching is not always straight and true so that these margins are often irregular as to width and the amount of fabric they contain.

In operating upon a bag for the resewing thereof, the operator brings that marginal part of the bag at its open end, into position against the front end of the flange 12 and moves it rearwardly so that said frayed margins are caused to enter the channel 30, with the side walls of the bag, passing under the lip 31 of the block like member 22. This lifts the block like member 22 against the action of the spring 27 and in effect provides a slot that opens laterally into said channel. The operator moves said end of the bag rearwardly and lowers the presser foot 4 to en-

gage the bag with the feed plate. With the usual foot pedal, the machine is started into operation, the needle 7 and loop caster 8 coacting to form an overcast stitch 35, the feed plate of the machine assisting in feeding the bag through the folder.

As the margins 33 of the bag enter the channel 30 the frayed portions thereof engage the curved surface 17 on the end of the platform 15 and the associated portion of the groove 29 in the block like member 22 so as to be turned outwardly and back over upon said margins to cover the original line of stitching 34 as best shown in Fig. 7.

As the margins with their turned over edge portions pass through the channel, they are tightly folded and compressed due to the rearward tapering conical formation of said channel, the spring 27 being of sufficient strength to hold the block like member 22 down to its work under ordinary conditions. However, if the bag is such as to have a margin of a bulk greater than that found in the general run of bags, then such a bulky margin will cause the block like member to be elevated against the action of the spring 27. Such increased bulkiness is usually found at the corner of the bag and such corners heretofore were hand trimmed to remove such bulk. This hand trimming is unnecessary with my improved folder because the block like member will lift upwardly to permit the bulky portion to pass through the channel and will then close down so soon as this bulky part has passed through the channel. In other words the block like member "floats" to accommodate such bulky portions. In this respect, it is pointed out as these margins pass through the channel, a heavy pressure is imposed upon the block member in a rearward direction and this pressure is amply resisted by the flanges 28 so that no binding of the block like member 22 can occur.

As the rear end of this channel is disposed but a short distance in advance of the needle, the needle 7 and loop caster 8 coact to provide the overcast stitching 35 before mentioned, to bind in and enclose all frayings and ravelings so that a neat appearing, double stitched, bound seam is provided for the bag as best shown at the top of Fig. 2 and in Fig. 7.

As before mentioned, the axial plane of the channel 30 is disposed to one side (the right hand side) of the perpendicular axial plane of the needle bar so that this brings the longitudinal loops of the overcast stitching inside the turned over portions of said margins with the lateral loops of said overcast stitching binding the edge of the new seam thus made.

As the bag is fed through the channel, said bag is turned as the corner thereof approaches the folder and then the closed bot-

tom end of the bag is fed through the folder until the entire side and bottom end has passed through the folder when the thread is cut and another bag is fed through the same way. In this respect, it is pointed out that the block like member 22 is of especial advantage when the bag is turned at said corner as it is at this point that the greatest bulk occurs due to the excess of bag material at this point and which heretofore was trimmed off by hand.

It is also pointed out that with the downwardly and rearwardly formed platform surface 16, the bag in its initial feed into the folder is brought into close engagement with the feed plate of the machine on the base and under the presser foot with but little effort upon the part of the operator.

While in describing the invention, I have referred in detail to the form, arrangement and construction of the various parts thereof, the same is to be considered merely as illustrative only, so that I do not wish to be limited thereto except as may be specifically set forth in the appended claims.

I claim as my invention:—

1. In combination with a sewing machine including a base, a presser foot and reciprocating needle bar, a member on said base to the front of the needle bar forming a platform having a downwardly and rearwardly extending top surface, means coacting with one end of said platform in providing an open top groove, and means supported above said groove and coacting therewith to complete a rearwardly tapering conical channel, said last mentioned means being mounted for a yielding guided movement toward and away from said groove and including a lip like flange extending laterally therefrom to overhang a part of said platform adjacent said groove.

2. In a folder of the kind described, a plate like member including a platform with a rearwardly and downwardly inclined top surface, means coacting with one end of said platform in providing an open top groove, a bracket on said member and including a part overhanging and disposed above said groove, a block like member slidably mounted in said overhanging part for movement toward and away from said groove and formed on its bottom with a surface to coact with said groove in providing a rearwardly tapering conical channel and means normally urging said block like member toward said groove.

3. In a folder of the kind described, a plate like member including a platform with a rearwardly and downwardly inclined top surface, means coacting with one end of said platform in providing an open top groove, a bracket on said member and including a part overhanging and disposed above said groove, a block like member slidably mount-

ed in said overhanging part for movement toward and away from said groove and formed on its bottom with a surface to coact with said groove in providing a rearwardly tapering conical channel, means normally urging said block like member toward said groove and a lip like member extending laterally from said block like member and overhanging the associated end of said platform.

4. In a folder of the kind described, a plate like member including a platform with a rearwardly and downwardly inclined top surface, means coacting with one end of said platform in providing an open top groove, a bracket rising from said plate member and including a boss overhanging said groove, a block like member mounted for guided movement in said bracket toward and away from said groove and which member is formed on its bottom to coact with said groove in completing a rearwardly tapering conical channel, a guide stem secured in said block like member and extending up through said boss and a spring surrounding a part of said stem and so engaging the block like member to urge the same downwardly toward said groove.

5. In a folder of the kind described, a plate like member including a platform with a rearwardly and downwardly inclined top surface, means coacting with one end of said platform in providing an open top groove, a bracket rising from said plate like member and including a boss overhanging said groove, a block like member mounted for guided movement in said bracket toward and away from said groove and which member is formed on its bottom to coact with said groove in completing a rearwardly tapering conical channel, a guide stem secured in said block like member and extending up through said boss and a spring surrounding a part of said stem and so engaging the block like member as to urge the same downwardly toward said groove, said block like member and bracket having engaging parts to resist a pressure in the direction of the length of the channel.

6. In a folder of the kind described, a plate like member including a platform with a rearwardly and downwardly inclined top surface, means coacting with one end of said platform in providing an open top

groove, a bracket rising from said plate member and including a boss overhanging said groove, a block like member mounted for guided movement in said bracket toward and away from said groove and which member is formed on its bottom to coact with said groove in completing a rearwardly tapering conical channel, a guide stem secured in said block like member and extending up through said boss and a spring surrounding a part of said stem and so engaging the block like member as to urge the same downwardly toward said groove, said block like member including a laterally extending lip like flange along one side at the bottom which overhangs the associated end of the platform.

7. In a folder of the kind described, a plate like member including a platform with a rearwardly and downwardly inclined top surface, means coacting with one end of said platform in providing an open top groove, a bracket rising from said plate member and including a boss overhanging said groove, a block like member mounted for guided movement in said bracket toward and away from said groove and which member is formed on its bottom to coact with said groove in completing a rearwardly tapering conical channel, a bushing adjustably mounted in said boss, a guide stem secured in said block like member and having a sliding engagement in said bushing and a spring surrounding said rod between said block like member and bushing and normally urging said block like member down toward said groove.

8. In combination with a sewing machine including a base, a presserfoot and a reciprocating needle bar, a member mounted on said base to the front of the needle bar forming a platform with a top surface having an open top groove near one end thereof, means fixed with respect to said end of said member and providing a pair of laterally spaced guide surfaces spaced above said groove and means mounted for a yielding guided engagement with said surfaces toward and away from said groove and formed on its underside to coact with said groove in providing a rearwardly tapering channel.

PAUL E. HAVEL.
